(57) **CLAIM**

The ornamental design for a slide out seal, as shown and described.

DESCRIPTION

FIG. 1 is a perspective view of a slide out seal, in accordance with the present invention;

FIG. 2 is a front elevation view of the slide out seal of FIG. 1, in accordance with the present invention;

FIG. 3 is a top plan view of the slide out seal of FIGS. 1-2, in accordance with the present invention;

FIG. 4 is a side elevation view of the slide out seal of FIGS. 1-3, in accordance with the present invention; and,

FIG. 5 is a bottom plan view of the slide out seal of FIGS. 1-4, in accordance with the present invention.

The slide out seal is shown broken along its length to indicate that the slide out seal may be formed in any length.
